UNITED STATES PATENT OFFICE.

IRA L. FULLER, OF GREENFIELD, INDIANA.

WEATHER FAN.

Application filed July 26, 1924. Serial No. 728,288.

To all whom it may concern:

Be it known that I, IRA L. FULLER, a citizen of the United States, residing at Greenfield, in the county of Hancock and State of Indiana, have invented a new and useful Improvement in Weather Fans, of which the following is a specification.

My invention relates to a fan in which the pitch of the blades may be varied at will either with the fan rotating or with the fan at rest. A fan is universally employed in a motor car to draw air through a radiator as a means of rapidly cooling the radiator. In the winter time, it is not necessary to draw as much, if any, air through the radiator as in summer time, and, in fact, it is often the case that due to a fixed bladed fan too much air is pulled through the radiator such that the radiator contents are cooled to a point below that which the engine operates efficiently, and in this case, since no practical working means had heretofore been developed, the only recourse has been to permit the fan to continue pulling air, but to cover the radiator to prevent the air from going through the radiator.

My fan may have the pitch of its blades varied at will even during the rotation of the fan so as to increase or decrease the amount of air pulled by the fan, and, in fact, the blades may be reversed so as to throw heated air from the engine back through the radiator. It is the primary object of my invention to incorporate means of varying the pitch of the fan blades within the hub of the fan such that the said means may be entirely inclosed and operative through the center fan shaft. Further objects reside in the simplification of construction, low cost of manufacture, extreme compactness, durability through long usage, and external means of controlling the pitch of the fan blades that may be extended to be operative at any distance from the fan.

I accomplish these and such other objects as may become apparent in the following description by the means as illustrated in the accompanying drawing, in which—

Fig. 1 is a vertical side elevation of a fan in which my invention is incorporated, the fan being here shown as mounted in the usual manner upon a motor, a fragment only of which is shown; Fig. 2, an enlarged front elevation of the fan with a fragment of the cover plate removed to disclose the construction in detail; Fig. 3, an enlarged horizon-

tal section taken on the line 3—3 in Fig. 1; and Fig. 4, an enlarged vertical section taken on the line 4—4 in Fig. 1.

Like characters of reference indicate like parts throughout the several views.

The hub of my fan is composed of two parts—the rear member 5 upon which is formed the driving pulley adapted to receive the belt 6, and the cover 7 which is centrally positioned on the member 5 by means of the annular ring 8 fitting within the annular groove 9 in the member 5, and the cover 7 is there retained by means of the two cap screws 10. A shaft 11, having the collar 12 to prevent outward travel of the member 5, passes centrally through the member 5 so as to allow the member 5 to revolve freely thereon, and extends with a reduced diameter through the support bracket 13, and is rigidly held in the bracket 13 in the usual manner by means of a lock nut 34 run up over the threaded end of the shaft 11 to contact the bracket.

The fan blades 14, here shown as four in number, are each mounted upon a spindle 15 which passes through a boss 16, half on the member 5 and half on the cover 7, and terminates in a disk 36, which is in sliding contact with one of the four walls 17 of the chambers formed within the forward portion of the member 5 and included under the cover 7, each of the four walls 17 forming a plane to which the axis of rotation of the fan is parallel.

The shaft 11 has a central axial passage 18 throughout its length, and in this passage 18, I screw-threadedly engage the adjusting bolt 19, such that by means of the key 20 through its tongue 21 being inserted within the oblong hole 22 in the end of the bolt 19, the bolt 19 may be turned upon its threads within the shaft 11 so as to be extended into or withdrawn from the chamber in the member 5 by turning the key 20 correspondingly.

A block 23 is centrally carried upon a reduced section of the forward end of the bolt 19 and is retained thereon between the locknuts 24 on the end of the bolt 19 and the collar 25, being so mounted as to revolve freely upon the bolt 19. The block 23 is of such dimensions that it may slide freely over the inner surfaces of the four disks 36 and at the same time serve as means of retaining the disks 36 in sliding contact with the respective walls 17. A T-slot is

formed within each side of the block 23 contacting the disks 36, and retained in each slot by its head, is a T-headed crank pin 26, the shank of which projects laterally outward and passes with a running fit through the corresponding disk 36.

Referring to Fig. 3 of the drawing, by turning the key 20 so as to cause the bolt 19 to travel toward the cover 7, the block 23 10 may be carried from the position indicated outwardly toward the cover 7 to a position as indicated by the dotted lines, and in so traveling, the block 23, by reason of the crank pins 26 retained therein and also being connected with the disks 36, will cause the disks 36 to revolve, thereby turning the spindles 15 so as to change the angle or pitch of the fan blades 14 correspondingly. As the disks 36 rotate, the heads of the 20 crank pins 26 slide longitudinally of the slots in the block 23. It will be noted that the disks 36 may be made to revolve through angles closely approximating 180 degrees in either the outward or inward travel of the 25 bolt 19 with its head block 23.

When the belt drives the fan, the shaft 11 and the bolt 19 within remain stationary such that the member 5 revolves on the shaft 11 and the block 23 revolves on the bolt 19. 30 The key 20 may be effectively locked to prevent its turning to change the pitch of the blades by drawing up the nut 28 to pinch the collar 29 on the key 20 against the end of the shaft 11.

35 While I have here shown one form of my invention, it is capable of many variations in structural form without departing from the spirit of the invention. I have shown the crank pins 26 as having T-heads so as 40 to be retained within the T-slots of the block 23 and have a running fit in the disks 36. These pins 26 may also be rigidly secured in the disks 36 in which event, the pins would have no heads and merely slide along 45 in straight slots in the block 23. Also, the means of adjusting or determining the position of the block 23 for a desired fan blade pitch may be varied from the screw-threaded means as shown and the bolt 19 be al-

lowed to slide freely through the passage 18 of the shaft 11 and project externally from the rear of the shaft 11 so as to be hooked up with lever, frictional, or other control devices operative at a distance from the fan, as, for instance, on the instrument board of a motor car. While I have here described my invention in the form of a radiator-cooling fan, it is obvious that it is equally applicable to any type of a propeller such as is used in aeroplanes and motor 55 boats.

I claim:

1. In a variable pitch fan, a tubular shaft; a hub rotatably retained on the shaft, said hub projecting beyond said shaft to define a chamber within the hub; a plurality of spindles rotatably mounted in said hub and entering said chamber; a head on each of said spindles within the chamber; a fan blade rigidly mounted on each of said 70 spindles without the chamber; a bolt carried within said tubular shaft, screw-threadedly engaging therewith, and projecting into said chamber; pivot means secured to said bolt within said chamber, said pivot means engaging each of said spindle heads; a key entering said tubular shaft to engage said bolt; and means of locking said key to prevent rotation or withdrawal thereof. 75

2. In a variable pitch fan, a tubular shaft; a hub rotatably retained on the shaft, and defining a chamber within; a plurality of spindles rotatably mounted in said hub and entering said chamber; a head on each of said spindles within the chamber; a fan blade mounted on each of said spindles without the chamber; a bolt carried within said tubular shaft, screw-threadedly engaging therewith, and projecting into said 80 chamber; pivot means secured to said bolt within said chamber, said pivot means engaging each of said spindle heads; and means to turn said bolt. 85

Signed at Indianapolis, county of Marion, 90 State of Indiana, this the 21st day of July, 1924.

IRA L. FULLER.
